(Cl. D17—8)

To all whom it may concern:

Be it known that I, Henry F. Gorth, a citizen of the Dominion of Canada, residing at St. Catharines, in the Province of Ontario and Dominion of Canada, have invented a new, original, and ornamental Design for a Combined Slider Body and Pull Tab for Slide Fasteners, of which the following is a specification, reference being had to the accompanying drawing, forming a part thereof.

In the drawing:

Fig. 1 is a plan view of a combined slider body and pull tab, showing my new design;

Fig. 2 is a side view thereof;

Fig. 3 is a top end view of the same;

Fig. 4 is a bottom end view thereof; and

Fig. 5 is a rear view of my new design.

I claim:

The ornamental design for a combined slider body and pull tab for slide fasteners substantially as shown.

HENRY F. GORTH.
